UNITED STATES PATENT OFFICE.

ANTON SOLMAN AND ALBIN SLIWINSKI, OF PITTSBURGH, PENNSYLVANIA.

PISTOL-SWORD.

1,207,235.

Specification of Letters Patent.

Patented Dec. 5, 1916.

Application filed September 7, 1916. Serial No. 118,840.

To all whom it may concern:

Be it known that we, ANTON SOLMAN and ALBIN SLIWINSKI, subjects of the Emperor of Austria-Hungary, residing at Pittsburgh, in the county of Allegheny and State of Pennsylvania, have invented certain new and useful Improvements in Pistol-Swords, of which the following is a specification.

This invention relates to certain new and 10 useful improvements in pistol swords.

The primary object of this invention is to provide an improved construction of a combined sword and pistol in which the sword, hilt, hand sheath, pistol magazine 15 and support are formed in an integral structure and which is shown in our co-pending application, Serial No. 118,841.

Another object of the invention is to provide a pistol sword in which the sword element has formed or cast integral therewith 20 a support or cradle for the reception of the barrel portion of an automatic revolver.

With these general objects in view and others that will appear as the nature of the 25 invention is better understood, the same consists in the novel construction, combination and arrangement of parts hereinafter more fully described, illustrated in the accompanying drawings, and then claimed.

30 In the drawings forming a part of this application and in which like designating characters refer to corresponding parts throughout the several views, Figure 1 is a side elevational view of a pistol sword constructed in accordance with the present invention, with the sword element partially broken away. Fig. 2 is a rear elevational view thereof, and, Fig. 3 is a detail perspective view of the hilt portion of the sword, 35 with the sword partially broken away.

Briefly described, the present invention has particular reference to the construction of a pistol sword wherein the sword element of the device includes novel details of construction.

45 The invention particularly relates to the forming or casting in an integral structure, the sword and the cartridge magazine or casing together with a carrier or cradle for the sliding barrel of an automatic pistol.

50 The construction and operation of the automatic pistol does not enter into the gist of the present invention but is shown, described and claimed in detail in our co-pending application, Serial No. 118,841.

55 Referring more in detail to the accom-

panying drawing, the reference numeral 5 designates an automatic pistol that is carried by a sword including the saber 6 and the hilt designated in general by the reference numeral 7.

The sword hilt 7 has removable side plates 8 that are secured to the central rib or main body-portion 9 of the hilt by screws or other suitable fastening means 65 passed through openings 10 formed in the hilt, it being understood that the hilt 9 is formed integral with the saber 6. A usual form of guard for the hand is provided and is indicated by the reference numeral 11, the 70 guard being constructed to encircle the hilt as is clearly shown in Figs. 2 and 3 and including a rearwardly-extending portion 12 formed integral with the rear end of the hilt 9.

75 One of the novel features of the present invention consists in constructing the cartridge casing or magazine integral with the sword hilt and saber, such casing being shown at 13 to depend centrally from the 80 hilt 9. A tensioned magazine 14 shown in dotted lines in Fig. 1 is associated with the casing 13 and is adapted to contain the cartridges and place the same under tension 85 for automatic feeding to the pistol 5.

The connecting portion of the device between the saber 6 and the hilt 9 is of increased cross-sectional area as indicated at 15 and the upper extremity of such portion 15 is constructed to provide a cradle 16 90 which includes opposite side walls or guides 17. The barrel 5 of the pistol as shown in Fig. 1 is slidably received in said cradle for the usual operation of an automatic pistol. A trigger 18 is provided for the pistol 5 95 and is pivotally mounted on the lug or pin 19 formed upon the hilt 9 of the sword and is operatively connected with the sear-controlled mechanism of the pistol 5, a portion of which mechanism passes through the 100 opening 20 formed in the enlarged section 15 of the saber 6 as is clearly shown in Fig. 3.

105 From the above detailed description of the invention it is clearly apparent that the sword element of the combination includes in its integral construction a portion of the pistol mechanism, such as the cartridge magazine or casing 13 and the pistol trigger 18 pivotally mounted upon the hilt 9 of the sword. The sword element also includes the 110 cradle 16 for the sliding reception of the sliding barrel of the pistol and, as before

stated, this cradle is also formed integral with the sword. As more clearly shown in Fig. 2, the portion of the hand sheath which surrounds the barrel of the pistol 5 is provided with a notch or recess 11' for purposes of sighting in connection with the device.

While the form of the invention herein shown and described is what is believed to be the preferred embodiment thereof, it is nevertheless to be understood that various forms, modifications and arrangement of the parts may be made without departing from the spirit and scope of the invention as claimed.

What I claim as new is:

1. In combination with the sliding barrel of an automatic pistol, an integral sword structure including a saber, a hilt, a cartridge casing, and a cradle for supporting the pistol barrel.
2. In combination with the barrel of an automatic pistol, a sword structure including a saber and a cradle formed integral with the saber for supporting the barrel.
3. In combination with the barrel of an automatic pistol, a sword structure including a saber, a cartridge casing, and a cradle

formed integral with the saber and casing and centrally disposed relative thereto, the said barrel adapted to be slidably mounted within the cradle for automatic operation.

4. A pistol sword comprising a sword element including an integrally formed hilt, a cartridge casing, a saber, a cradle superposed upon said cartridge casing and saber, and an automatic sliding pistol barrel mounted in said cradle.

5. A pistol sword comprising a cartridge casing carried by the sword element, and a cradle formed integral with said sword and extending forwardly thereover, and an automatic sliding pistol barrel mounted in said cradle.

6. A pistol sword comprising a saber and hilt section, a hand sheath formed integral therewith and having an opening at the upper end thereof, a pistol barrel slidably mounted within said opening, and a sight notch formed in said hand sheath above said pistol barrel.

In testimony whereof we affix our signatures.

ANTON SOLMAN.
ALBIN SLIWINSKI.
